UNITED STATES PATENT OFFICE

GEORGE A. ROBINSON, OF BRAINTREE, MASSACHUSETTS, ASSIGNOR TO JOHNSON AUTOMATIC SEALER CO., LTD., OF BATTLE CREEK, MICHIGAN

GLUE-APPLYING MECHANISM

Original application filed January 4, 1927, Serial No. 158,978. Divided and this application filed May 17, 1928. Serial No. 278,583.

This invention relates to glue applying mechanism adapted for use in carton making machines or in association with any instrumentality where the use of such mechanism is desirable.

One object of the invention is to provide an improved mechanism that operates automatically to apply adhesive to the sealing flap of a carton blank or the like.

Another object of the invention is to provide an improved glue applying mechanism the operation of which is controlled by the presence of a blank therein.

Another object of the invention is to provide an improved glue applying mechanism that conserves the supply of adhesive while at the same time applying the proper amount thereof to the blank to insure efficient sealing.

A further object of the invention is to provide a simply constructed, inexpensive and highly efficient glue applying mechanism not likely to get out of order and requiring minimum attention by the operator.

Other objects of the invention will appear as the following description thereof proceeds.

This application is a division of my co-pending application Serial No. 158,978, filed January 4, 1927, and in order to more clearly understand the invention herein disclosed and claimed, reference may be had to the accompanying drawings wherein like reference characters designate like parts throughout the several views.

In said drawings:

Fig. 1 is a side elevation of a carton making machine equipped with glue applying mechanism embodying the present invention;

Fig. 2 is a detail perspective view of the glue applying mechanism and devices for feeding a blank through the same and into the carton making machine;

Fig. 3 is a detail perspective view of a detector device controlling the operation of the glue applying mechanism; and

Fig. 4 is a detail perspective view of a conveyor for carrying blanks to said devices and said mechanism.

The glue applying mechanism as herein shown, is associated with, and preferably driven from, a carton making machine. The carton making machine per se forms no part of the present invention and it is therefore unnecessary to describe the same in detail. It is sufficient to note that said machine includes the usual side frames 5 for supporting the carton making and conveying instrumentalities (not shown) together with blank feeding means and the glue applying mechanism which are preferably driven and constructed as follows.

Journalized in suitable bearings on the side frames 5 is a shaft 6 that is provided with a pulley 7 which may be driven from any suitable source of power 8 through a belt 9 that passes around a pulley 10 fixed on a shaft 11 (Fig. 1). The shaft 11 is journalized in suitable bearings on the side frames 5 and carries a pulley 12 around which passes a belt 13 that also passes around the pulley 7 and thereby drives the shaft 6. Carried on the shaft 6 is a clutch 14 the loose part of which carries a pinion 15 which meshes with a gear 16 that is fixed on a shaft 17 journalized in suitable bearings on the side frames 5. The clutch 14 is controlled by a clutch lever 18 to thereby control the drive for shaft 17 from which the blank carrying and feeding devices, as well as the glue applying mechanism are driven.

The shaft 17 carries on one end thereof a sprocket 19 which is adjustably secured on a disk 20 that is fixed on said shaft. A sprocket chain 21, which passes around the sprocket 19 also passes around a sprocket 22 which is fixed on a shaft 23 journalized in suitable bearings on frame pieces 24. The frame pieces 24 are supported on frame pieces 25 which in turn are supported as by legs 26 and 27 on the frame pieces 5 and the machine foundation respectively. Journalized in suitable bearings on one of the frame pieces 24 is a short vertical shaft 28 the upper end of which has fixed thereon a bevel gear 29. The bevel gear 29 meshes with a bevel gear 30 fixed on the shaft 23 which thus serves to drive the shaft 28. Fixed on the lower end of the shaft 28 is

a bevel gear 31 that meshes with a bevel gear 32' which is fixed on a shaft 32 extending longitudinally of the machine and journaled in suitable bearings on one of the frame pieces 24 and one of the frame pieces 25. The shaft 32, which is thus driven from the shaft 28, has fixed thereon a worm gear 33 which meshes with a worm gear 34 which is fixed on a shaft 35 journaled in suitable bearings on the frame pieces 24. The shaft 35 has fixed thereon a sprocket 36 around which passes a chain 37 that also passes around a sprocket 38 that is fixed on a shaft 39 journaled in suitable bearings on the frame pieces 24. Fixed on the shaft 39 is a spur gear 40 that meshes with a spur gear 41 which is fixed on a shaft 42 journaled in suitable bearings on the frame pieces 24. The shafts 35 and 42, together with the above described gearing connecting the same, serve to drive opposed blank carrying tapes 43 and 44 between which the blanks B are fed successively by hand or by suitable mechanism for this purpose such as described in my copending application Serial No. 158,978, above referred to. The tapes 43 and 44 pass around suitable pulleys which are fixed on shafts 35 and 42 and on shafts 45 and 46, the last named shafts being journaled in suitable bearings on the frame pieces 24. The pulleys on the shafts 35 and 42 are indicated at 47 and 48 respectively (Fig. 4) and the pulleys on the shafts 45 and 46 are indicated at 49 and 50 respectively. As each blank B is carried forwardly by the tapes 43, 44 a side sealing flap C of said blank is bent upwardly by a flap bender 51 (Fig. 4). This flap bender may be of any suitable construction such, for example, as disclosed in my copending application Serial No. 158,978, and since said flap bender forms no part of the present invention, it is unnecessary to describe the same in detail. The blank B with the sealing flap C bent up, is then carried forwardly by the tapes 43, 44 and delivered to a turning roll 52 which takes the blank, turns it angularly to said tapes and delivers it to feed rollers which feed the blank past the glue applying mechanism and then into the carton making machine as will presently appear. The turning roll 52 may be of any suitable construction such, for example, as disclosed in my copending application Serial No. 158,958, and since said turning roll forms no part of the present invention it is unnecessary to describe the same in detail. It is sufficient to note that the turning roll 52 is fixed on a shaft 53 which is journaled in suitable bearings on the frame pieces 25 and driven through the medium of a bevel gear 54 fixed on the shaft 32 and a bevel gear 55 that meshes with the bevel gear 54 and is fixed on the shaft 53 (Fig. 2).

The turning roll 52 at a certain time in its operation, releases the blank B which is then delivered to means for feeding the blank past the glue applying mechanism and into the carton making machine. Said means may be of any suitable construction but as herein disclosed the same preferably comprises two sets of feeding rolls which are located below the turning roll. The upper set of feeding rolls between which the blank first passes are indicated at 56 and 57 and are driven at the same surface speed as the turning roll 52. Beneath the rolls 56, 57 is a second set of feeding rolls which are indicated 58, 59 and driven at a somewhat higher rate of speed in order to feed the blank rapidly into the carton making machine.

The rolls 56 are carried on a shaft 60 mounted in suitable bearings on the frame of the machine and are driven by means of a sprocket 61 mounted on the shaft 60, a sprocket 62 mounted on the turning roll shaft 53, and a sprocket chain 63 which passes around the sprockets 61 and 62. The rolls 58 are carried on a shaft 64 mounted in suitable bearings on the machine framework and driven through a sprocket 65 mounted on shaft 64, a sprocket 66 mounted on the shaft 60, and a chain 67 which passes around the sprockets 65 and 66. The rolls 57, which bear against the rolls 56, are carried on a shaft 68 that is journaled in the upwardly extending arms of bell-cranks 69 mounted loosely on a shaft 70. Suitable springs 71 bearing against the rearwardly extending arms of bell-cranks 69, press the rolls 57 yieldingly against the rolls 56. The rolls 59 are mounted on a shaft 72 journaled in the lower ends of arms 73 clamped on the shaft 70. The shafts 64 and 72 are rotated together by means of a pair of gears 74 and 75, respectively. The shafts 60 and 68 are rotated together positively by means of gears 76 and 77 mounted on said shafts.

Carried in suitable bearings on the machine framework and disposed adjacent the rolls 56, 57, is a horizontal shaft 78 (Fig. 2) which carries at one end a glue roll 79. This glue roll 79 runs in a glue pot 80 and is provided with a scraper 81 to control the amount of glue on the glue roll 79. The shaft 78 is provided with a sprocket 82 around which passes a sprocket chain 83 driven from a sprocket 84 mounted on the continuously revolving time shaft 32. The glue roller 79 is therefore rotated while the machine is operating and stops its rotation whenever the clutch 14 is disengaged and the machine is stopped. It is preferred that this gluing roller shall be driven only when the machine is running and shall be stopped when the machine is stopped. Inasmuch as the machine may be stopped by

hand while a carton blank is passing between the rollers 56 and 57 and while the blank is in contact with the gluing rolls, if the glue roll does not stop when the machine is stopped the continued rotation of the glue roll while in contact with the side sealing flap would tend to throw the blank out of position in the machine.

Mounted on a shaft 85 journaled in suitable bearings on the machine framework, is a rubber covered glue roll 86 which turns in contact with the glue roller 79 and is driven therewith through a gear 87 mounted on shaft 78, which gear engages with a gear 88 mounted on shaft 85. A pressure roll 89 is carried on a shaft 90 mounted on the upper end of an arm 91 pivoted at 92 in the glue roll bracket. Shaft 90 is provided with a gear 93 which meshes with gear 88 on shaft 85 thereby driving the roll 89 at the same speed as the roll 86. The arm 91 is moved to the left as viewed in Fig. 2 through the action of a connecting rod 94 attached to the upper end of the arm 91, the other end of the connecting rod being attached to a bell-crank lever 95 pivoted at 95' on a stationary part of the machine. The lever 95 carries a roll 96 which bears against a cam 97 on shaft 32. Movement to the left of arm 91 carries the roll 89 thereon away from the roll 86. The roll 89 is urged toward the glue roll 86 through the action of a spring 98. It is desirable to hold the pressure roll 89 out of contact with the glue roll 86 unless there is a carton blank present to receive a stripe of glue from the glue roll 86. Means are therefore preferably provided whereby, if a carton blank is not present between the feeding rollers 56 and 57, the arm 91 with the pressure roll 89 is held in an outward position against the action of the spring 98. This means is preferably comprised by the following instrumentalities.

Mounted on the arm 91 is a finger 99 (Fig. 3) which is fixed on one end of a shaft 100 journaled on said arm, the other end of the shaft 100 being provided with a detector finger 101 which projects into the downward path of travel of the carton blank. The lower end of the finger 99, in its normal position is adapted to engage the end of a pin 102 carried in a stationary part of the glue roll bracket. When the finger 99 engages the end of the pin 102, it holds the arm 91 in its outward position against the action of the spring 98. When the carton blank is fed into position to receive a stripe of glue on the side sealing flap, the advancing edge of the carton blank strikes the detector finger 101 and swings the finger 99 out of engagement with the pin 102. Under these conditions, when the roll 96 rides off the high part of the cam 97, the arm 91 is allowed to rock and swing the roller 89

into contact with the side sealing flap C of the blank, which flap is then pressed by the roller 89 firmly against the glue roll 86. The cam 97 is shaped so that the pressure roll 89 is moved into engagement with the blank just as the side sealing flap passes between the glue roll 86 and said pressure roll and the cam moves the pressure roll out of contact with the side sealing flap just before it passes out of engagement between the glue roll and the pressure roll. This insures that there will be no glue deposited on the pressure roll, as any glue on this roll would be deposited on the inside of the side sealing flap where it would cause the carton to stick on the carton form and interfere with the proper operation of the machine.

A guide 103 is provided which is carried by the arm 91 to guide the carton properly past the glue rolls and after the blank passes the glue rolls, it is fed by the rolls 58, 59 into the carton making machine to be acted on by the instrumentalities which make the blank into a carton or container. While the glue applying mechanism is herein disclosed in association with a carton making machine, said mechanism may be used independently or in association with any other instrumentality with which the use of glue applying mechanism is desirable.

It is therefore to be expressly understood that the present invention is not limited to the particular embodiment thereof herein disclosed or otherwise than by the terms of the appended claims.

What is claimed is:

1. In combination, a glue roller and a pressure roller bodily movable relatively in opposite directions, blank feeding means extending substantially at right angles to the axes of the glue and pressure rollers and adapted to feed a carton blank so that a flap bent from the body of said blank passes between said rollers, means for moving one roller toward and away from the other as the bent flap passes therethrough whereby glue is applied on one side of the bent flap by said glue roller, and means movable with and relative to one roller for preventing relative bodily movement of the rollers in the event a blank is not fed by said feeding means.

2. In combination, a glue roller and a pressure roller, an arm on which one of said rollers is mounted for movement toward and away from the other roller, means for swinging said arm, a stop device, and a blank controlled member pivoted on the arm and controlling the swinging movement thereof through engagement of said member with and disengagement of the same from said stop device.

3. In combination, a glue roller and a pressure roller, a pivotally mounted arm on which one of said rollers is carried, means

for swinging the arm whereby the roller thereon is moved toward and away from the other roller, a shaft journaled on the arm, a stop device, and a blank operated member fixed on said shaft and controlling the swinging movement of said arm through engagement of said member with and disengagement of the same from said stop device.

4. In combination, a glue roller and a pressure roller, a pivotally mounted arm carrying one of said rollers, means for swinging the arm in opposite directions so that the roller thereon is moved toward and away from the other roller, a stop element arranged adjacent the path of movement of said arm, means pivoted on the arm adapted to swing in one direction to engage the stop element and thereby prevent swinging movement of the arm, and a blank operated detector for swinging said means in the opposite direction to prevent its engagement with said stop element.

5. In combination, a glue roller and a pressure roller, means for driving both rollers, a pivotally mounted arm carrying one of said rollers, means cam-operated in one direction and spring-operated in the opposite direction, for swinging the arm so that the roller thereon is moved toward and away from the other roller, a rock shaft journaled on the swinging arm, a stop and blank operated means carried on said rock shaft adapted to control the swinging movement of said arm through engagement of said blank operated means with and disengagement of the same from said stop.

6. In combination, a glue roller and a pressure roller, a pivotally mounted arm carrying said pressure roller, means for swinging the arm so that the pressure roller is moved toward and away from the glue roller, a rock shaft journaled on the arm substantially at right angles to the pivotal axis thereof, a stationary stop element disposed in spaced relation with the swinging arm, a stop member on said rock shaft adapted to engage the stop element and prevent swinging movement of the arm, and a finger on the rock shaft adapted to be engaged by a carton blank to rock said shaft whereby the stop member thereon is prevented from engaging said stop element.

7. In combination, a glue roller and a pressure roller, rotatable devices having their axes extending substantially at right angles to the axes of the glue and pressure rollers, said devices being adapted to feed a blank so that a flap bent angularly to the blank body passes between said rollers, means for moving one roller toward the other to engage the flap therebetween and apply glue to one side of said flap, a stop, and a blank controlled member movable with and relative to said roller moving means and adapted to control the operation

thereof through engagement of said member with and disengagement of the same from said stop.

8. In combination, a glue roller and a pressure roller, means for driving one roller including a driven gear fixed on the axis thereof, means for driving the other roller comprising a gear fixed on the axis thereof and meshing with said driven gear, means for bodily moving the rollers relatively in opposite directions to thereby apply adhesive to a blank, a stop, and a blank controlled member movable with and relative to said roller moving means and adapted to control the movement of the latter through engagement of said member with and disengagement of the same from said stop.

9. In combination, a glue roller, means for driving the glue roller including a driven gear fixed on the axis thereof, a pressure roller, means for driving the pressure roller comprising a gear fixed on the axis thereof and meshing with said driven gear, means for moving the pressure roller toward and away from the glue roller to provide for application of glue thereby to a blank, a stop pin, a blank controlled member movable with and relative to said roller moving means and adapted to control the movement of the latter through engagement of said member with and disengagement of the same from stop pin, and means for pivotally mounting said blank controlled member on the roller moving means.

10. In combination, a glue roller, means for driving the glue roller including a driven gear fixed on the axis thereof, a pivotally mounted arm, a pressure roller mounted on the arm, means for moving the arm and the pressure roller toward and away from the glue roller to provide for application of glue thereby to a blank, means for driving the pressure roller comprising a gear fixed on the axis thereof and meshing with said driven gear, a stationary stop pin arranged adjacent the path of movement of the pivotally mounted arm, and a blank controlled member pivoted on said arm substantially at right angles to its pivotal axis and adapted to control the bodily movement of the arm and the pressure roller through engagement of said member with and disengagement of the same from said stationary stop pin.

11. In combination, a glue roller and a pressure roller, a member on which one of said rollers is mounted, means adapted to feed a blank past the rollers to be engaged therebetween and receive adhesive from the glue roller, means on said member for guiding the blank during its movement past the rollers, means for moving the member and the roller carried thereby toward and away from the other roller, a stop device, and a

blank controlled element pivoted on said member and controlling the movement thereof through engagement of said element with and disengagement of the same from 5 said stop device.

12. In combination, a glue roller and a pressure roller, a pivotally mounted arm carrying the pressure roller, means for feeding a blank past the rollers to be engaged 10 therebetween and receive adhesive from the glue roller, a guide member on the pivotally mounted arm for guiding the blank during its movement past the rollers, means for swinging the arm and the pressure roller 15 toward and away from the glue roller, a stop device, and a blank controlled member pivoted on said arm and controlling the movement thereof through engagement of said member with and disengagement of 20 the same from said stop device.

In testimony whereof I have signed this specification.

GEORGE A. ROBINSON.
